CLAIM

The ornamental design for a humidifying air purifier as shown and described.

DESCRIPTION

1. Humidifying air purifier

1.1 : Perspective

1.2 : Front

1.3 : Back

1.4 : Left

1.5 : Top

1.6 : Bottom

1.7 : Exploded

The broken lines depict portions of the humidifying air purifier that form no part of the claimed design; the dash-dot broken lines define the boundary of the claimed design and form no part thereof; reproduction 1.4 is a left view where the right view is a mirror image; reproduction 1.7 is an exploded view showing the exploded state of the upper part; as shown in reproduction 1.1, the humidifying outlet and air purifying outlet are separated by double transparent win-

(Continued)

dows; this design can allow the user to see rising steam generated from water in the water tank at inside center through the double transparent windows.
